UNITED STATES PATENT OFFICE.

IVAR CORNELIUSSEN, OF GALVESTON, TEXAS.

HYDRAULIC MOTOR.

Application filed November 10, 1924. Serial No. 748,865.

This invention relates to new and useful improvements in a hydraulic motor.

One object of the invention is to produce an apparatus of the character described whereby the rising and falling of water may be utilized, and converted into power for practical purposes, through the instrumentality of a float, or floats, and a suitable mechanism, operatively connected with said float, for converting the power into practical form for utilization.

With the above and other objects in view this invention relates to certain novel features of construction, operation and arrangement of parts an example of which is given in this specification and illustrated in the accompanying drawings, wherein:

Figure 1 shows a vertical sectional view of the apparatus, as constructed for utilizing the ebb and flow of the tide, taken on the line 1—1 of Figure 15.

Figure 2 shows a horizontal sectional view taken on the line 2—2 of Figure 1.

Figure 3 shows a plan view, partly in section, of one of the floats employed.

Figure 4 shows a fragmentary vertical sectional view of the power converting mechanism, mounted on the float.

Figures 5 and 6 show plan and side views, respectively, of a power transmitting clutch mechanism employed.

Figures 7 and 8 show front and end elevations, respectively, of said clutch mechanism.

Figure 9 shows an enlarged fragmentary sectional view of the sheaves, and the mounting thereof, constituting part of said power transmitting mechanism.

Figure 10 shows a cross sectional view thereof, taken on the line 10—10 of Figure 9.

Figure 11 shows a cross sectional view thereof taken on the line 11—11 of Figure 9.

Figure 12 shows a plan view of a form of the device designed to utilizing the rise and fall of water, other than tide water.

Figure 13 shows a vertical sectional view thereof.

Figure 14 shows a vertical sectional view taken on the line 14—14 of Figure 13 and

Figure 15 shows a horizontal sectional view of the apparatus showing a diagrammatic view of the respective floats and associated water connections, taken on the line 15—15 of Figure 1.

Referring now more particularly to the drawings, wherein like numerals of reference designate similar parts in each of the figures, the numerals 1, 1 designate spaced channels, or ways, erected on suitable piers 2, out in the water which is subject to the flow and ebb of the tide.

These channels are preferably constructed of concrete, and are covered but are open toward the sea or other body of water. Between these channels there is an enclosed float chamber 3, of the nature of a coffer dam whose side walls are common with the adjacent side walls of the channels 1, 1, and whose ends are of concrete and formed to completely exclude the water. Near the ground surface the chamber 3 has an outlet opening 4 which may be opened and closed by a gate valve 5 operable through the rod 6, which carries a hand wheel 7, on top of the chamber, through which the valve may be operated.

In the channels, and float chamber there are the floats, 8, 8 and 10, respectively. Each float 8 has a transverse rotatably mounted shaft as 11, whose end has a pinion 12 fixed thereon and in mesh with a similar pinion 13 mounted to rotate on said float 8. There is a vertical shaft 14 whose upper end has a bearing in the bracket 15 fastened to the top of the corresponding channel 1. The lower end of this shaft has a bearing in the pier 16 beneath the channel and carries a turbine wheel 17 which is located in the inlet end of the water conduit 18 which leads out through said pier 19, beneath the chamber 3, and continues up through said pier and on up through the float 10 and is then turned downwardly into a discharge chamber 20, in said float 10, and is controlled by a gate valve 21.

The conduit 18 is formed with a suitable slip joint 22, supported on the pier 19. Located in the outlet chamber 20 there is a turbine 23 which is fixed on the lower end of the vertical shaft 24, and this shaft 100 has a fixed pinion 25 in mesh with a similar pinion, 26 fixed on the adjacent end of the transverse shaft 27. Underneath the chamber 3 and the other channel 1, respectively, are the piers 28, 29. The upper end of the pier 28 has the inlet end of a water conduit 30 leading downwardly therethrough and outwardly turned, and which enters and leads up through the pier 29 and on up through the corresponding float 8 and is 110

then downwardly turned into the outlet chamber 31 of the said float 8. This conduit is formed with a slip joint 32, supported on the pier 29, and is controlled by the gate valve 33. The inlet end of the conduit 30 has a turbine 34 located therein which is fixed on the lower end of a vertical shaft 35. This shaft extends up through the float 10 and its upper end has a bearing in the bracket 36 carried by the top of the chamber 3. The float 10 supports a transverse rotatable shaft 37, similar to the shaft 27, and fixed on one end thereof there is a pinion 38 in mesh with a similar pinion 39, carried by the float 10 and splined on the shaft 35. In the outlet chamber 31 there is a turbine 40 which is fixed on the lower end of the vertical shaft 41. The upper end of this shaft has a fixed pinion 42 which is in mesh with a similar pinion 43, which is fixed on the adjacent end of a transverse shaft 44, all carried by the corresponding float 8.

When the tide comes in the floats 8, 8 will rise with it, the port 4 being closed to prevent the inflow of water into the chamber 3. The gate valve 21 may be opened to admit water, through the conduit 18 into the chamber 3 and the inflowing current will rotate the turbines 17 and 23 and, in turn, will drive the shafts 11 and 27. Upon ebb of the tide the valve 21 being closed the valve 33 may be opened and the water in the chamber 3 will flow out through the conduit 30, rotating the turbines 34 and 40 as it escapes. From these turbines the shafts 37 and 44 are driven. The shafts 11, 27, 37 and 44 are power delivery shafts and may be utilized to drive electric generators, or any other mechanism desired, located on the corresponding floats. If it be desired to more quickly release the water in the chamber 3 the port 4 may be opened, for this purpose.

The floats 8, 8 rise and fall with the tide, but the movements of the float 10 may be somewhat controlled through the valves 21 and 33.

The rising and falling of the floats may be utilized through suitable power converting mechanism, carried by them, and which will now be described, a description of the mechanism of one float being sufficient for all, since they are similar in essential particulars.

Referring to Figures 1 and 3, the float 10 is shown with four pairs of end sheaves, adjacent the corners of the float, and indicated, collectively, by the numerals 45, 45' and 46, 46'. Near the respective ends of the float are the pairs of large sheaves rotatable in horizontal planes, the sheaves of each pair being concentric and indicated by the numerals 47 and 48 respectively. Between these pairs of sheaves there are two counter shafts 49, in vertical alignment and rotatably mounted on the float 10 and fixed on

which are the adjacent spools 50, 51, with pairs of guide pulleys 52 arranged on opposite sides, as shown in Figure 3.

A number of cables are provided, each cable being attached at one end to one of the piers 2 and at its other end to the top of the corresponding channel 1. One of these cables is indicated by the numeral 53. It passes up over the corresponding end sheave 45, and around the top sheaves 47 and 48, being wound around the corresponding intermediate spool 50, and working on the guide pulleys 52, and it passes then around under the opposite pulley 46. As the float moves in one direction this cable will rotate the spool 50 and the shaft 49 on which the spool is fixed. Another cable 54 is attached, at its upper end, as explained, and it passes around under the sheave 45' and around the upper pulleys 47, 48, being wound around the intermediate spool 51 and held thereon by the guide pulleys 52. This cable passes thence around over the pulley 46 and its other end is attached to the corresponding pier 2, beneath, and as the float rises the cable 54 assists in driving the upper shaft 49.

In a similar manner the cables 55 and 56, operate over the sheaves 45, 46 and 45', 46', respectively, and around the lower sheaves 47 and 48 the lower spools 50, 51, to drive the lower counter shaft 49.

The float 10, which is taken as an illustration, and which, in the particulars hereinafter stated, is similar to the other floats, has a transverse partition 58, forming a platform, or flooring, for the support of operative mechanism, and also forming one or more ballast chambers 10' beneath it.

In Figure 3 a section of the top of this float is broken away, revealing reduction ascending gearing 59, employed, and which includes a jack shaft 60, which is driven from the shafts 49, through sprocket wheels, 61, 61 fixed on the shafts 49, and driving 110 through the chains 62, 62, which operate over suitable sprocket wheels fixed on said jack shaft.

The ultimate driven shaft 63 has a fixed sprocket 64 thereon which drives the 115 sprocket chain 65. This chain operates over, and drives, a sprocket wheel 66 which is fixed on the counter shaft 67 rotatably mounted on the platform 58. The shaft 67 carries a worm gear 68 which is located between, and in mesh with, the rack faces 69, 69 of the oppositely disposed pulleys 70, 70. Around the respective pulleys 70 are the cables 71, 71 which are coiled around the drums 72, 72 and are confined thereon by the guide pulleys 73, 73. The drums 72 are fixed on the power shafts 74, 74 each of which carries also the fixed sprockets 75, 76.

It is obvious that as the float 10 rises the

rotation of the mechanism hereinbefore described, including the shafts 74, will be in a direction the reverse of its movement when the float falls. In other words the shafts 74 will rock back and forth. It is necessary to convert this rocking movement into a constant drive in one direction and this result is accomplished through the mechanism, now to be described:—operating over the sprockets 75, 76, and driven thereby are the respective sprocket chains 77, 78. The chains 77 operate over, and drive, the sprockets 79, loosely mounted on the respective shafts 80, 80. The inner ends of the hubs of the sprockets 79 are formed into clutch jaws 81, 81. The chains 78, 78 have outside drive connections with sprockets 82, 82, which are loosely mounted on the shafts 80, and said chains are maintained in mesh with said sprockets 82 by means of the idlers 83, 83 over which the chains 78 operate. The inner ends of the hubs of the sprockets 82 are formed into clutch jaws 84, 84. Splined on the shafts 80, between the clutch members 81 and 84 there are the clutch members 85, 85, whose respective ends are also formed with jaws adapted to engage the respective jaws 81 and 84 when said last named jaws are driven forwardly, but to be disengaged, when said clutch jaws are reversely driven.

When the shaft 74 is driven in one direction it will drive its corresponding sprocket 79 in a direction to cause the clutch jaw 81 to maintain driving engagement with the clutch member 85 and the shaft 80 will be correspondingly rotated. Meanwhile the sprocket 82 will idly rotate reversely with respect to the rotation of sprocket 79. Now upon reverse rotation of shaft 74 the clutch member 85 will be automatically disengaged from the clutch jaw 81 and carried into engagement with the clutch jaw 84, which upon reversal of the shaft 74 has also reversed, as to its rotation, and now continues to drive the shaft 80 in its original direction. Beneath the shaft 80 are the spaced brackets 87 and 88 and the clutch lever 89 is pivotally mounted between them. The upper end of this lever is formed into a yoke 90, which engages in the annular groove 91 of the clutch member 85. Fastened to the inside of the bracket 88 there is a lock plate 92, which is provided with vertical slots 93 to receive the securing bolts 94 on which the plate is vertically adjustable. The upper end of this plate is formed with a lug 95, for a purpose to be hereinafter stated. There is a shift plate 96, pivoted to the lower end of the clutch lever 89. This plate has a long transverse bearing 97 in which a sheave 98 runs and a weight 99 is suspended from this sheave. The plate 96 rocks on its pivot connection with the lever 89 but the range of its movement is limited

by the spaced stops 100, 100 arranged on opposite sides of the lever 89. The plate 92 has the oppositely disposed, upwardly curved slots 101, 102 in which the inner end of the pin 103, supporting the plate 96, is adapted to work.

As shown in Figure 7 the clutch jaw 81 has reversed its rotation and the sloping face 104 thereof, operating against the corresponding sloping face 105 of the cooperating jaw of the clutch member 85 has disengaged said jaws, and forced the member 85 lengthwise, on the shaft 80, toward the clutch jaw 84. The lug 95 operating against the lug 104' has just swung the plate 96 into the position shown and the weight 99 will cause the lower end of the lever 89 to swing around, the pin 103 moving to the outer end of the slot 102, carrying the lug 104' past the lug 95 and forcing the plate 96 downwardly until the lug 95 thereof again engages behind the lug 104', carried by the upper edge of the plate 96, and as said lever 89 swings around as stated the clutch member 85 will be carried into engagement with the clutch jaw 84. When the clutch jaw 84 is reversed the sloping face 105' thereof, operating against the corresponding face 106, of the member 85, will disengage said jaws and force the member 85, along on the shaft 80 toward the jaw 81. This will operate to swing the lower end of the lever 89 in the opposite direction and the lug 104', operating against the lug 95, as a fulcrum, will operate to swing the plate 96 in the opposite direction to that shown in Figure 7, causing the weight to run to the other end of the bearing slot 97 and the weight will cause the lower end of the lever 89 to swing over, carrying the lug 104' past the lug 95, and carrying the pin 103 along the slot 101 thus lowering the plate 92 and engaging the lug 95 behind the lug 104' and carrying the clutch member 85 into engagement with the clutch jaw 81.

The shafts 80 have the fixed sprockets 107 which drive the chains 108, and these chains in turn drive the power delivery shafts 109, through the reduction ascending gearing 110, 110.

In Figures 9, 10 and 11 I have shown an enlarged fragmentary view of the reduction gearing employed. The shaft, as for example shaft 63, on which the sprockets are mounted has a lengthwise oil channel 111, into which the lubricant is fed from the cup 112. The pairs of sprockets, as for example 113, 114 are spaced apart by the sleeve-like spacer 115'. The members of each pair are formed on a common hub 122 within which there is a wedge-like soft metal packing, formed in lengthwise sections 115, 115 and lined by the sectional bearing sleeve 116. The hub 122 is formed, at one end, with radial slots 117, as shown in Fig. 9 and

radial clamps 118 work in the slots 117, and abut against the large ends of the wedge sections 115. These clamps are formed with extended shanks 119 which work in lengthwise bearings in the hub 122, and whose outer ends are threaded to receive the nuts 120, which are located in side recesses 121, carried by the hub 122. Through these nuts, and the clamps 118 adjustable thereby, the packing 115 may be adjusted, as desired. This form of packing may be very quickly adjusted or replaced and is therefore particularly adapted for the type of device herein described.

The bearings are lubricated from the channel 111, through the radial ducts 123, leading therefrom.

In Figures 12, 13 and 14 a form of the device has been shown adapted to utilize water power other than that derived from ebb and flow of the tide. The numerals 123 and 124 designate similar adjacent float chambers, and the numeral 125 designates a reservoir which is elevated above said chambers. A suitable motor driven pump 126 is mounted on said reservoir and connected with the suction and discharge pipes 127, 128 by means of which water may be pumped, as needed, from the sluice way, or other water supply, 129 into said reservoir. Floats, as 10, are located in said chambers 123 and 124. These float chambers have valve controlled outlets 130, 131 into the sluice way 129, at their bottoms, and there is a valve controlled connecting conduit, or port 132, at the bottom of these chambers, through which water may pass from one to the other.

The reservoir 125 also has valve controlled outlet ports 133, 133 through which water may be admitted from the reservoir to the respective float chambers. The conduits and ports 130—133 are controlled by conventional, hand operated gate valves, as 124.

As shown in Figure 13 the chamber 123 is full and the chamber 124 empty and the reservoir is also assumed to be full and the valves 134 all closed. The port 132 is now opened and the water will rise in the chamber 124 and fall in the chamber 123 to a common level, and said port 132 then closed. The floats 10 respectively will rise and fall in a corresponding manner, and will operate the mechanism, hereinbefore described, which is mounted in said floats, but not shown in Figures 12—14. In this movement of the floats 10 both the buoyancy of one, and gravity acting on the other will be utilized. The outlet 130 may now be opened to drain the chamber 123 and its float will further descend, generating power in its descent. The outlet 130 is then closed and the port 133, above the chamber 124 opened and said chamber completely filled lifting

the float 10, thereof to the top of the chamber, and the said port 133 is then closed. The port 132 may now be again opened to equalize the water level in the float chambers and then closed and said floats will move, one up and the other down, to a common level, each generating power by such movements. The chamber 124 may be now drained, and the chamber 123 filled on up, as above explained, thus moving the floats 10 correspondingly, with a resultant generation of power.

What I claim is:—

1. A device of the character described including an enclosed chamber, a float therein, an inlet water conduit entering said chamber and provided to deliver water into the chamber beneath the float, power delivery mechanism carried by the float, means mounted on the float and actuated by the flow of fluid through said conduit and operatively connected with said mechanism to drive the same. 80

2. A device of the character described including an enclosed chamber, a float therein, an inlet water conduit entering said chamber and provided to deliver water into the chamber beneath the float, power delivery mechanism carried by the float, means mounted on the float and actuated by the flow of fluid through said conduit and operatively connected with said mechanism to drive the same, a driving member on said float, a flexible member in operative connection with said driving member, and having its ends attached to fixed anchors, said flexible member operating said driving member in harmony with the float, as it rises and falls, a driven member carried by the float and operatively connected with the driving member. 90

3. A device of the character described including an enclosed chamber, a float therein, an inlet water conduit entering said chamber and provided to deliver water into the chamber beneath the float, power delivery mechanism carried by the float, means mounted on the float and actuated by the flow of fluid through said conduit and operatively connected with said mechanism to drive the same, an outlet conduit leading out from said chamber beneath the float, and valves controlling said conduits. 110

4. A device of the character described including an enclosed chamber, a float therein, an inlet water conduit entering said chamber and provided to deliver water into the chamber beneath the float, power delivery mechanism carried by the float, means mounted on the float and actuated by the flow of fluid through said conduit and operatively connected with said mechanism to drive the same, an outlet conduit leading out from said chamber beneath the float, said chamber having a discharge port beneath the float, 120

125

130

and valves for controlling said conduits and said port.

5. A device of the character described including a plurality of floats located to be affected by tide water, an enclosed chamber in which one of the floats is located, an inlet water conduit entering the enclosed chamber and adapted to discharge water therein beneath said float, an outlet conduit leading out of said chamber from beneath the float therein, valves controlling said conduits, means carried by the respective floats and adapted to be driven by the current through said conduits, and power delivery means on the respective floats and in operative connection with and driven by said current driven means.

6. A device of the character described including an enclosed chamber, a plurality of floats located so as to be affected by the tide water, and one of which is enclosed within said chamber, a turbine carried by each float, an inlet water conduit entering the enclosed chamber and adapted to discharge water therein beneath the float, an outlet leading out of said chamber from beneath the float therein, valves controlling said conduits, said turbines, carried by the respective floats, being disposed to be driven

by the current through said respective conduits and power delivery means on the respective floats and in operative connection with and driven by the corresponding turbines.

7. A device of the character described including an enclosed chamber, a plurality of floats located so as to be affected by the tide water, and one of which is enclosed within said chamber, a turbine carried by each float, an inlet water conduit entering the enclosed chamber and adapted to discharge water therein beneath the float, an outlet leading out of said chamber from beneath the float therein, valves controlling said conduits, said turbines, carried by the respective floats, being disposed to be driven by the current through said respective conduits, other turbines in each of said respective conduits, power delivery means on the respective floats and in operative connection with and driven by the corresponding turbines, said chamber having a port beneath the float and a valve for opening or closing said port.

In testimony whereof I have signed my name to this specification.

IVAR CORNELIUSSEN.
